SIGURD NORMAN, OF NEWBERG, OREGON

METHOD OF CONSERVING THE HEAT AND PULP FROM PULP-DRYING MACHINES

Application filed January 29, 1929. Serial No. 335,993.

The primary object of my new and improved process is to increase the capacity of a pulp drying machine.

A further object of my new and improved 5 method consists in conserving the heat used in a pulp drying machine and making the same available for use.

A further object of my new and improved 10 method consists in conserving pulp losses heretofore exhausted from pulp and paper making machines.

A further object of my new and improved 15 method is to make the room of the pulp drying machine of a pulp plant, in which the drying machine is disposed, more healthful place for workmen while engaged in their duties, as pulp makers, by eliminating dust and pulp particles from the air of the room.

The device consists primarily of a condensing 20 chamber through which the heated air leading from the drying machine, which at the present time is normally exhausted into the air, is passed in a heated condition and a chamber in which water jets are released 25 in compartments of the condensing chamber progressively, to precipitate the pulp particles carried in the air, to extract the heat disposed in the air and utilize the same for heating the water to be used in the pulp mass and thereby admit a warmed pulp mass to the 30 drying machine.

As a superintendent of pulp mills, I have observed that the drying process may be greatly speeded up and therefore the capacity 35 of the drying machine be increased when warm pulp is admitted into the drying machine. The primary reason for this being that if highly heated air is admitted into the drying machine at the entrance end of the pulp sheet into the machine, and if the pulp sheet is relatively thick and cold, that the surface of the sheet is dried at once, leaving a cold wet core and the drying surface forms an insulation for the further extraction of 40 the moisture within the core is greatly slowed up and requires a longer time for the sheet to remain within the drying machine; whereas, if a warmed sheet made from warm water is admitted into the machine, the drying 45 process may be greatly speeded up. The

utilization of the heat formerly exhausted from the drying machine to the atmosphere is sufficient when extracted to warm the water, so that a warm pulp sheet is made and admitted into the drying machine. The passing 55 of the exhausted air from the drying machine through the condenser and water jets released in the various compartments precipitates particles of pulp carried in suspension in the air which is returned to the mixing vat. 60

With these and incidental objects in view, the invention consists in certain novel features of construction and combination of parts, the essential elements of which are set forth in the appended claim, and a preferred 65 form of embodiment of which is hereinafter shown with reference to the drawings which accompany and form a part of this specification.

I have illustrated in the drawings, suitable 70 mechanism that may be utilized in the carrying out of my new and improved process, in which:

Fig. 1 is a side view of a pulp drying machine and illustrating the source of supply 75 from which the pulp mass is received and the machine for forming the pulp sheet.

Fig. 2 is a cross section view of the condensing chamber.

Fig. 3 is a cross section view, taken on line 80 3-3 of Fig. 2, looking in the direction indicated.

Like reference characters refer to like parts throughout the several views.

1 is the mixing vat into which the pulp mass 85 is admitted in a relatively cold state, the same is mixed and warmed in the vat and is then pumped through a pump 2, into a vat 3 in which the sheet forming machine 4 is disposed. The sheet is delivered into the entrance end 5 of the drying machine 6. Air is induced into the drying machine through the fans 7. The drying machine is of the usual type for heating the air admitted into the drying machine. I place a condensing chamber 8 adjacent the drying machine and exhaust the air therefrom through the outlet 9 leading from the drying machine into the condenser 8. The condenser 8 is divided into a plurality of compartments by baffle walls 95 100

10 and water for condensing is admitted through the inlet pipe 11 and is released in a fine spray from the discharge head 12. The same is collected within the base of the condenser and flows by gravity into a pressure pump 13 where sufficient pressure is developed to respray the water through a second spray head 13 where it is again collected within the base of the condenser and passes to a 15 second pressure pump 14 and it is again redistributed through the pressure head 15.

10 I have here shown three sprays being disposed within the condensing chamber, but I do not wish to be limited to any number of 15 sprays, as the number of sprayings should be sufficient to extract the heat disposed within the air admitted into the chamber. A multiple of compartments may be required depending upon the capacity of the drying machine. 20 The warmed water containing the precipitated particles of pulp are passed through the pipe 16 to the mixing vat 1 thereby providing heated water containing the precipitate pulp mass in sufficient quantity to warm the pulp from which the sheet is made.

25 While the form of mechanism herein shown and described is admirably adapted to fulfill the objects primarily stated, it is to be understood that it is not intended to confine the invention to the one form of embodiment herein shown and described, as it is susceptible of embodiment in various forms all coming within the scope of the claim which follows.

30 What I claim is:

35 The herein described continuous method of utilizing the heat of a drying chamber and retrieving the pulp particles held in suspension by the heated vapor consisting in driving the vapors into a condensing chamber, 40 spraying water upon the vapors, utilizing the spent spray a plurality of times, and finally conducting the condensed vapors and retrieved matter in a warm condition to a mixing chamber.

45 SIGURD NORMAN.
